UNITED STATES PATENT OFFICE.

FLAVIO CANOVA, OF SCRANTON, PENNSYLVANIA.

DESIGN FOR A TOOTHPICK-HOLDER.

48,708.

Specification for Design.

Patented Mar. 14, 1916.

Application filed November 20, 1915. Serial No. 62,651. Term of patent 14 years.

To all whom it may concern:

Be it known that I, FLAVIO CANOVA, a citizen of the United States, residing at Scranton, in the county of Lackawanna and State of Pennsylvania, have invented a new, original, and ornamental Design for Toothpick-Holders, of which the following is a specification, reference being had to the accompanying drawing, forming a part thereof.

In the drawings: Figure 1 is a perspective

view; Fig. 2 is a top plan view; and Fig. 3 is a bottom plan of a tooth pick holder, showing my new design.

I claim:

The ornamental design for a tooth pick holder, as shown.

FLAVIO CANOVA.
